B. C. DOPPES ET AL

SPARK PLUG TESTER

Filed March 21, 1921

INVENTORS:

Bernard C. Doppes and

Harry W. Centner,

BY John Elias Jones,

ATTORNEY.

UNITED STATES PATENT OFFICE.

BERNARD C. DOPPES AND HARRY W. CENTNER, OF CINCINNATI, OHIO.

SPARK-PLUG TESTER.

Application filed March 21, 1921. Serial No. 454,176.

To all whom it may concern:

Be it known that we, BERNARD C. DOPPES and HARRY W. CENTNER, both of us citizens of the United States of America, and residing at Cincinnati, in the county of Hamilton and State of Ohio, have jointly invented a certain new and useful Improvement in Spark-Plug Testers, of which the following is a specification.

10 This invention relates to testing implements for use in connection with spark-plugs for internal-combustion engines; and its object is to provide a convenient hand-tool that has a spark space or gap in its structure that responds to a short circuit through the tool itself when applied to the spark-plugs and in plainly visible sight of those having automobiles, gas-engines, motor-cycles, aeroplanes, motor-boats, farm-
15 tractors in their use, or those having public garage service and others employing electric ignition in the operation of the said class of machines.

20 A special object of the invention is to produce a device of said character that shall be simple and durable in construction, inexpensive and easy to manufacture, and which will always be efficient and reliable in its testing application.

30 The invention consists of the novel features of construction, combination and arrangement of parts which will be herein-after referred to and more particularly pointed out in the description and claim.

35 In the accompanying sheet of drawings, Figure 1 is a perspective view showing our invention herein complete and in position for application; Fig. 2, a central, longitudinal section; and Fig. 3, a longitudinal elevation showing the testing device in using position at the upper end of a spark-plug.

40 4 indicates a suitable wooden handle having a narrow longitudinal kerf or slit 5 that extends about half its length.

45 6 indicates a flat strip of insulating material whose inner end is tightly clamped within the said kerf 5 of the handle by means of a pair of screws 7, 7. Strip 6 extends outwardly a suitable distance from the handle to receive and hold at its outer end a flat metal strip or plate 8 that is duly secured by means of a rivet 9. An aperture 10 is pierced in the outer end of the strip 8 to facilitate its proper engagement with the

upper extension stem 11 of the spark-plug 55 12, the latter being of any ordinary or approved type and mounted on the engine 13, a small fragment only of the latter being shown.

The inner end of the metal strip or plate 60 8 tapers to a point or tip 14, as best shown in Fig. 1.

15 is a short metal strip or narrow plate mounted on the upper surface of the said insulating strip 6, to the rear of the said metal strip or plate 8, being duly secured in place by means of a rivet 16 and having a vertical leg member 17 extending downwardly, at a right angle, through a transverse slot 18^a that is made in the said insulating strip 6 a slight distance forward of the fore end of the handle 4. The fore end of the short metal strip or plate 15 tapers to a point or tip 18 similar to the tip 14 at the inner end of the metal strip 8 and is duly spaced therefrom to produce the required gap for testing the spark in the plug 12 in the desired operation of the engine. In such testing operation, if no ignition current is present on account of any defects or 80 a lack of battery, the absence of a spark in the gap will of course be immediately disclosed, while, on the other hand, the visible spark in the said gap will instantly indicate or disclose normal working conditions 85 of the ignition current. The upper end of the metal leg member 17 is secured by means of a rivet 19 to the outer face of a broad transverse guard plate 20 that is made of insulating material and provided with a 90 horizontal slot 21 through which the first-named insulating strip 6 passes from the handle 4, the inner face of said guard plate being arranged to lie in contact with the end of the said handle from which the said insulating strip 6 projects. The said guard strip is intended for use in protecting the hand from contact with the current when using the implement herein in testing the plug for ignition service. The extreme 100 lower end of the metal leg member 17 of the spark indicating strip 15 extends to and in contact with the upper part of the engine 13 for grounding through the latter in effecting or closing circuit of the current 105 across the spark gap between the points 14 and 18. The two narrow metal strips or plates 8 and 15 are short ones so that the

path therethrough shall be more direct and the spark more positively effected in the said gap for the testing service.

It is obvious that instead of providing the aperture 10 in the outer end of the metal strip 8 the metal can be struck up into a flange or protuberance, thereby leaving a socket or stop on the underside of the strip 8 for the ready placement or setting on the top stem 11 of the spark-plug, but the setting or placing of the tool in testing position would not be as positive or as free from slipping or shifting sidewise. Besides, the said aperture affords a convenient means of 15 hanging the tool on a hook or nail handy to the user.

We claim:—

In a hand testing implement for spark-plugs of electric ignition internal-combustion engines, the combination of a suitable handle, an insulating strip extending longitudinally from one end of said handle, an insulating guard plate having a transverse slot through which said insulating strip on 25 the handle extends outwardly, a short nar-

row metal strip extending from the outer end of the said insulating strip and having a pointed inner end, and a narrow metal strip mounted on the upper surface of said insulating strip immediately forward of 30 said guard plate but to the rear of the pointed inner end of the said short metal strip and also having a pointed outer end that corresponds to that at the adjacent but spaced pointed inner end of the first-named 35 metal strip to produce the desired detecting or testing spark gap, and a pendent integral metal strip extending through a transverse slot made in the said insulating strip at a right angle from the inner end of the said rear metal plate on the said insulating strip to a point below the lower edge of said insulating guard plate for grounding a short circuit through the engine and producing a 40 spark in the said gap when ignition current is normally intact in the spark-plug, substantially as herein shown and described. 45

BERNARD C. DOPPES.
HARRY W. CENTNER.
